UNITED STATES PATENT OFFICE.

FREDERICK L. KANE, OF HUNTINGTON, NEW YORK.

PLASTER-SUPPORT FOR WALL-COVERING.

1,003,754.

Specification of Letters Patent. Patented Sept. 19, 1911.

Application filed July 15, 1910. Serial No. 572,088.

To all whom it may concern:

Be it known that I, FREDERICK L. KANE, of the town of Huntington, county of Suffolk, and State of New York, have invented 5 a new and useful Improvement in Plaster-Supports for Wall-Covering, of which the following is a full, clear, and exact description.

My invention relates to improvements in 10 that class of devices and materials used for attachment to the studding of a wall or ceiling beams as a means for supporting a plaster body or coating, the support being intended as a substitute for lath. A common means is to produce sheets of material 15 of combined and alternating layers of paper and plaster which are attached to the wall and plastered over, and paper and other fabrics have also been used instead of lath, 20 the paper and other material being attached to the studding as plaster board. There is a great advantage in using paper either in sheets or rolls or of a laminated structure, because of the fact that it can be readily 25 handled, attached, and shipped, and because of the further fact that it is cheap; but a serious difficulty arises from the fact that the plaster is of necessity applied wet, and when it is applied to the paper in this condition 30 the paper becomes saturated and weakened, and so sags and sometimes breaks before the plaster body becomes set, and where it sags seriously, the resulting wall is of course distorted and unsightly. I 35 have found, however, that I can take suitable paper having a surface adapted to receive a plaster layer or coating, and use the paper either perforated or unperforated, but preferably perforated, and stiffen the 40 paper by applying numerous transverse strips preferably of metal to it, so that when these strips are attached to the studding or ceiling beams they will effectually prevent the paper and the attached plaster 45 from sagging or breaking away, and still extending as they do transversely of the paper strip, they will permit the latter to be rolled like ordinary paper. In carrying out this idea I prefer to use a laminated paper, and the stiffening strips can be attached 50 in such a way that the act of fastening the stiffening strips to the paper will serve to fasten the laminæ or sheets together, while they also stiffen the whole and make it 55 easier to handle without tearing the paper.

This will be better understood from the description which follows.

Reference is to be had to the accompanying drawings forming a part of this specification, in which similar reference characters indicate corresponding parts in all the views.

Figure 1 is a perspective view of a sheet of fabric, preferably paper of a suitable kind, provided with my improved stiffening means. Fig. 2 is a cross section of a wall provided with my plaster support and with a layer of plaster attached. Fig. 3 is a cross section of a wall showing how the adjoining sheets overlap when attached. Fig. 4 is an enlarged detail sectional view showing a preferred means of attaching a stiffening strip to the paper, and Fig. 5 is a broken face view of a wall with the plaster broken away, and showing the manner in which the paper or fibrous plaster support is applied.

The strip 10 of paper or fibrous material, but preferably paper, is long enough so that it can be rolled up as shown in Fig. 1, for convenience in shipping and applying, and it may be in a single sheet or laminated, and it is also preferably provided with perforations 11 so that the plaster can pass through the perforations and clench as shown in Fig. 2, but if the paper is of a reasonably loose texture the plaster adheres to it perfectly, even though it is not perforated. I prefer to make the paper sheet of several laminæ 12, as shown in Figs. 2 and 4, and these are held together by any suitable cement which will not be too hard but will be of a flexible nature so as to permit the paper to roll readily. Ordinary coal tar pitch is suitable for this purpose. The paper which serves as the wall support is attached to the studding 13 of a wall, and as above remarked, if it were unsupported, it would sag and sometimes break under the weight of the wet plaster which is attached to it, and to obviate this I provide numerous strengthening strips 14 which can be of any approved material but which are preferably thin sheet metal such as steel or iron, and these are securely fastened to the paper preferably on the side which comes next to the plaster, though the strips can be attached to either side or lie within the paper sheet, if desired. I do not limit myself to any particular means of

fastening the strengthening strips to the paper, but I prefer to use thin flat strips as shown, and these can be died out as shown at 15 so as to form struck-up brads 5 16 which are forced through the paper layers and clenched, as clearly shown in Fig. 4. This makes a light yet exceedingly strong strengthening rib or brace, and it does not in any way interfere with the handling of the sheet, but on the contrary strengthens it and makes it easier to handle, while at the same time it permits it to be readily rolled. I wish it distinctly understood, however, that while I have shown the 10 preferred form of strip and means of attachment, yet I do not limit myself to any shape or to any fastening means, but as shown the fastening means serves to strengthen the cement by which the layers 15 are secured together, and holds them so that they cannot very well be separated.

When the wall support is applied to the studding 13, the sheets 10 are laid parallel with the studding and are made preferably 20 in such widths that one sheet will extend across the distance of two studs and overlap the next adjacent sheet, though obviously they can be made in various widths. When attached the strips 14 are arranged transversely of the studs 13 and with the adjacent edges of the strips overlapping, as shown at 18 in Figs. 3 and 5. The fastening nails 19 are all driven through the strips 14 and through the support or paper into 25 the studding 13. It will be seen, therefore, that it is not the mere stiffening of the paper which results from the attachment of the strengthening ribs 14, but that when the support is applied to the studding and the nails 30 driven through the soft material, the latter will have to be stretched before it will break, and so the paper is stiffened according to the tensile strength of the strengthening ribs or strips, as the said strips are held taut and 35 must either break or pull out the nails before permitting the plaster support to sag.

The plaster is applied as usual in a layer 40 so that it will pass through the perforations of the paper and cover the strips 14, 45 but in the use of the word paper I wish it understood that I refer to any analogous fibrous material of a paper-like character.

From the foregoing description it will be 50 clearly seen that I have produced a flexible 55 easily handled cheap material which can be readily attached to the studding of a wall or ceiling beams, and which when so attached forms a secure support for plaster and is not likely to be warped or distorted 60 under the weight of the wet plaster. It will

further be seen that the material which I use is entirely flexible so that it can be handled and applied much better than the stiff sheets often used for the purpose. Attention is also called to the fact that material 65 for wall coverings is shipped in large quantities, and that the freight item is a large one. But my improved covering is so flexible that it can be rolled into a tight compact roll, and cheaply shipped and easily 70 handled. I wish to call attention to the further fact that the thin metallic strips 14 lie flat and snug on the paper, thus presenting a smooth, flat surface, and the plasterer can thus easily apply the plaster to the supporting paper and less plaster is required than on many materials which present rough or bulky exterior surfaces, which must necessarily be covered by the plaster.

I claim:—

1. A support for wall plaster comprising paper board of such flexibility as to be compactly rolled and of such width as to span the stud spacing of a wall and spaced thin, flat strengthening strips extending transversely of and applied to one surface of the board and through fasteners engaging the surface of the said board opposite the said strips, said fasteners being connected to the strips.

2. A wall support for plaster comprising a flexible paper board capable of being compactly rolled and of a width equal to the said spacing of a wall or multiple thereof, and thin, flat strengthening strips spaced 95 apart and extending transversely of the board and fasteners integral with the strips extending through and clenching on the side of the board opposite that engaged by said strips.

3. A support for wall plaster comprising a laminated sheet of fibrous material, and thin flat strengthening strips extending across the sheet, said strips having fastening devices integral thereon and extending through 105 the laminae.

4. A support for wall plaster comprising a sheet of laminated paper board providing a plaster hold sufficiently thin to be capable of being rolled and in width equal to the 110 stud spacing of a wall or a multiple thereof and spaced thin flat transverse strengthening strips applied to one surface and secured by through fastenings engaging the other surface of said paper board.

FREDERICK L. KANE.
